DESIGN FOR A COFFEE MAKER

Abe O. Samuels, Rochester, N. Y., assignor to Samson-United Corporation, Rochester, N. Y.

Application November 17, 1933, Serial No. 49,775

Term of patent 3½ years

To all whom it may concern:

Be it known that I, Abe O. Samuels, a citizen of the United States, residing at Rochester, in the county of Monroe and State of New York, have invented a new, original, and ornamental Design for a Coffee Maker, of which the following is a specification, reference being had to the accompanying drawing, forming a part thereof.

I claim:

The ornamental design for a coffee maker, as shown.

ABE O. SAMUELS.
